UNITED STATES PATENT OFFICE.

WILLIAM M. WHEILDON, OF BOSTON, MASSACHUSETTS, ASSIGNOR TO LIBRARY BUREAU, OF BOSTON, MASSACHUSETTS, A CORPORATION OF NEW JERSEY.

LOOSE-LEAF BINDER.

No. 893,120.

Specification of Letters Patent.

Patented July 14, 1908.

Application filed March 21, 1907. Serial No. 363,581.

To all whom it may concern:

Be it known that I, WILLIAM M. WHEILDON, a citizen of the United States, and resident of Boston, in the county of Suffolk and 5 State of Massachusetts, have invented new and useful Improvements in Loose - Leaf Binders, of which the following is a specification.

My invention relates to the mechanical adjuncts of loose leaf books, and consists in 10 sundry improvements in the clamping backs wherewith the leaves composing such books are bound.

In the drawings hereto annexed which 15 illustrate an embodiment of my invention and improvements, Figure 1 is an elevation of the clamping book back; Fig. 2 is an end view of portion of the book composed of loose leaves held by the clamping back 20 shown in Fig. 1; Fig. 3 is the vertical section of the clamping book back taken on the line 3—3 of Fig. 1; Fig. 4 is a detail showing the mode of operation of the releasing key lever; Fig. 5 is a detail showing my improved telescoping post and a mode of securing the same 25 to the side plates of the leaf holding clamp; and Fig. 6 is a cross section of one of the said telescoping posts showing the mode by which a leaf is held thereby.

Referring to Figs. 1, 2 and 3, A is the back plate and B, B the movable side plates which 30 constitute the principal members of the leaf holding clamp. The back plate A terminates in flanged end plates A³ which overlap and mask the ends of the side plates B, B. The side plates B, B serve for the attachment 35 of the flexible book covers as K seen best in Fig. 2. These side plates are movably connected to each other by means of the telescoping posts C whereof I have shown three in 40 the drawings. The operating devices which serve to expand or spread the side plates B, B apart, consist in the illustration shown of toggle gear, these being shown composed 45 of each of the links G and G' pivotally secured to the internal ears B' on the side plates B, and by cam studs G² on the bosses A² (Fig. 3). The double toggle gear is operated by means 50 of the swinging arm D which is pivoted at D² on the back plate A and which is provided with socket flanges D' suited to the reception of a key lever presently to be described. A plate E slotted at E' so as to be guided by the studs G² constitutes the connection be- 55 tween the two sets of toggle gear which are

pivoted at G³ to the plate E. A short link D⁴ pivoted to the rocking arm D at D³ is also pivotally secured to one of the studs G³ which is made to project from the back of the plate E for the purpose. Thus, when the 60 arm D is rocked one way or the other, the side plates B through the intervening means of the toggle gear will be expanded or brought together, the telescoping posts C opening and closing and assisting to hold the two side 65 plates B, B in proper position and alinement. The back plate A is slotted at A³ (Fig. 3) so as to provide an opening for the entrance of a key lever such as J.

Secure to the back plate A there is provided the ratchet sector F which coöperates with a spring controlled pawl H which is pivotally secured to the arm D. The arrangement of this pawl and ratchet is shown in detail in Fig. 4. I provide an operating handle, 70 in the specific instance shown in the drawings as the key lever J, which on being inserted through a proper opening such as the slot A³ in the back plate A dislodges the pawl H from its engagement with the ratchet F and 75 thus prepares the internal mechanism for further operation by movement of the handle J. In the specific device shown in the drawings the handle or key lever J is forked at J' so as to straddle the pin D³ and is furnished also 80 with a projection J² which is so proportioned that when the key lever J is inserted between the two flanged jaws D' the projection J² strikes against a pin H' upon pawl H. The key lever J or its projection J² may be so 85 fashioned that the mere act of inserting the key to its place operates to dislodge the pawl H from its hold on the ratchet F, or as indicated in Fig. 4, some further movement of the key lever J may be required as a rocking 90 or tipping movement to the left as shown in Fig. 4, which causes the projection J² to press the pawl H out of engagement with the ratchet F. When the releasing or unlocking 95 function of the handle or key lever J has been performed, a further movement of the handle suffices to rock the arm D to the left as shown in Figs. 1 and 4 and thereby slide the plate E longitudinally of the back plate and spread apart the two side plates through the agency 100 of the toggle gear. When leaves have been removed from or added to the assemblage thereof which constitutes the book, the two side plates B may be brought together, firmly clamping the mass of leaves. The 105 110

usual mode of clamping the leaves is merely to bear down hard on one of the side plates B as the book rests upon a table. The toggle gear collapses, the arm D is swung back and the pawl H coöperating with the ratchet F holds the arm D and the connected mechanism in any position to which it is brought.

In Figs. 1, 2 and 3 the binding clamp is shown as partly open, that is to say the side plates B are not as near together as the structure of the telescoping post C and toggle gear permits. The telescoping posts are made up of post members C which are precisely alike and interchangeable one with the other.

15 These posts are made each of a strip of sheet metal rolled or bent so that the cross section thereof very nearly approaches the shape of a figure 8. One loop of this double convolution is smaller than the other, its external 20 diameter being substantially the same as the internal diameter of the larger loop and the edge of the larger loop approaches but does not touch the curved surface of the post toward which it is bent. In Fig. 5 I have 25 shown one of these posts in elevation and in Fig. 6 the two posts are shown interlocked, one of them being in cross section. The slit left between the terminus of the larger curve of the post member C and the back of the 30 reverse curve is just sufficient to admit the body of the companion post member and by inserting these posts one within the other, causing the smaller convolution of each to enter the larger convolution of the other, 35 there is provided a telescoping post, several of which, when arranged as shown in Fig. 1, serve effectively to keep the leaves P in proper alignment. A portion of one of these leaves is shown in Fig. 6 illustrating the manner in which the binding posts C retain the 40 leaves P. To secure the members of the binding posts to the side plates B, I employ rivets, such as L, shown in Figs. 3 and 5.

The operation of the above described leaf holding clamp is easily and quickly performed by inserting the handle J through the slot A' and between the jaw flanges D', therewith disengaging the pawl and ratchet and thereafter moving the said plates B apart 50 through the medium of the toggle gear. The slow and comparatively laborious operation of working a screw with a key to open the toggles—a mode heretofore used—is thus obviated and improved upon and the leaf holding clamp as a whole rendered more convenient than such contrivances have been heretofore.

What I claim and desire to secure by Letters Patent is:

60 1. In a binder for loose leaf books, the combination of a back plate, movable side plates, telescoping posts connecting the side plates, an operating arm, connected to the expanding gear, the expanding gear a detent 65 and its coöperating member, one of these

stationary in relation to the back plate, the other on the expanding gear operating arm, and means, controlled by a key, to release the detent from its coöperating member, to free the arm for operating the expanding 70 gear.

2. In a binder for loose leaf books, the combination of a back plate, movable side plates, mechanism for opening and closing the side plates, and telescoping posts, each 75 consisting of an intertwined pair of S-sectioned members, said members being mutually interchangeable, one secured to one side plate, the other to the other.

3. In a binder for loose leaf books, the 80 combination of a back plate, movable side plates, telescoping posts connecting the side plates, expanding gear for the side plates, an operating arm pivoted to the back plate, a sliding middle-plate, connections therewith 85 to the expanding gear and to the operating arm, a rack stationary with relation to the back plate, a pawl coöperating therewith on the operating arm, and means controllable by a key to release the pawl to free the arm 90 for operating the expanding gear.

4. In a binder for loose-leaf books, the combination of a back plate, movable side plates, telescoping posts connecting the side plates, toggle gear for the side plates, operating means for the toggle gear, comprising a 95 detent and its coöperating member, one of these secured stationary in relation to the back plate, and means to release the detent and free the toggle gear operating means. 100

5. In a binder for loose leaf books, the combination of a back plate, movable side plates, telescoping posts connecting the side plate, toggle gear, for the side plates, an operating arm, connected to the toggle gear, a 105 detent and its coöperating member, one of these stationary in relation to the back plate, the other on the toggle gear operating arm, and means, controlled by a key, to release the detent from its coöperating member, to free the arm for operating the toggle gear.

6. In a binder for loose leaf books, the combination of a back plate, movable side plates, telescoping posts connecting the side plates, toggle gear for the side plates, an operating arm pivoted to the back plate, a sliding middle-plate, connections therewith to the toggle gear and to the operating arm, a rack stationary with relation to the back plate, a pawl coöperating therewith on the operating 115 arm, and means controllable by a key to release the pawl to free the arm for operating the toggle gear. 120

Signed by me at Boston, Massachusetts, this 19th day of March, 1907.

WILLIAM M. WHEILDON.
